Specification for Design.

Patented Nov. 29, 1921.

Application filed October 11, 1920. Serial No. 416,330. Term of patent 3½ years.

To all whom it may concern:

Be it known that I, JOSEPH M. CRUCET, a citizen of the United States, and a resident of the city of New York, county and State of New York, have invented a new, original, and ornamental Design for an Electric-Lamp Fixture, of which the following is a specification, reference being had to the accompanying drawings, forming part thereof.

The drawing is a perspective view of an electric lamp fixture, arranged in accordance with the present design.

I claim:

The ornamental design for an electric lamp fixture as shown.

JOSEPH M. CRUCET.
